UNITED STATES PATENT OFFICE.

FRANK RIESS, OF INDIANAPOLIS, INDIANA, ASSIGNOR TO RIESS MANUFACTURING COMPANY, OF KOKOMO, INDIANA, A CORPORATION.

COMBINED METAL-WORKING MACHINE.

Application filed July 25, 1925. Serial No. 46,173.

The machine herein shown and described is constructed and operated so that it may do a wide variety of work, particularly drilling, spinning, riveting, punching, hammering and tapping. It is a power machine operated by foot.

The object of the invention is to provide one machine which is readily adaptable for drilling, spinning, tapping, riveting, punching, hammering and like treatment of metal.

One feature of the invention is the provision of means for operating the spindle so that it may be simultaneously rotated and vertically reciprocated, or only vertically reciprocated, or only rotated, as desired for the particular work in hand, and particularly in constantly driven machines. In addition to the foregoing there is the provision of levers for varying the speed of the means for reciprocating the spindle to adapt it for drilling or riveting or other variety of work, along with the associated means for operating the spindle. Still another feature is the adjustable eccentric or cam construction for reciprocating the spindle and controlling the extent of the actuating movement thereof.

The full nature of the invention will be understood from the accompanying drawings and the following description and claims:

In the drawings, Fig. 1 is a central vertical section through the machine, centrally broken away. Fig. 2 is a front elevation of the upper part of the machine. Fig. 3 is a horizontal section on the line 3—3 of Fig. 1, looking downward. Fig. 4 is a section on the line 4—4 of Fig. 1, looking downward, parts being broken away. Fig. 5 is a front elevation of the cam mechanism for operating the spindle with the parts shown on a larger scale and in altered position from the position shown in Figs. 1 and 2.

This is a power machine and the form herein shown is operated by foot. The pedal 10 is on a pedal lever 11 fulcrumed at 12 in the base frame 13 and the pedal is held in elevated position by a spring 14 which is connected with the inner end of the lever and to the base frame at 15. The pedal lever is pivoted to the lower end of a vertically movable rod 16 that extends up within a tube 17, which at its lower end is secured by rivets 18 to the base frame 13 and on its upper end there is a tubular frame 19.

The tubular frame 19 has an upper fixed

arm or jaw 20 and under it a vertically adjustable arm or jaw 21 which carries in its outer end a member 22 on which the work is mounted that is to be treated. Substitute forms of the member 22 are employed according to the character of the work to be treated. The lower arm 21 is secured to the tubular frame 19 by bolts 23 extending through slots (not shown) to permit the vertical adjustment of the arm 21.

The fixed arm or jaw 21 carries in its outer end a vertically reciprocable spindle 25 which is in line with the center of the member 22 on the lower arm 21 and a tool of any desired type is mounted in or carried by the lower end of the spindle for treating the work on the member 22. Said spindle is rotated when desired by a spiral gear 26 splined thereon so that the spindle may reciprocate vertically, while the spiral gear 26 does not move vertically as it is between the upper part of the arm 20 and the housing 27 secured thereon by screws 28. The spiral gear 26 is driven by a spiral wheel 29 located between the arm 20 and housing 27, as shown in Fig. 1, and mounted on a shaft 30, as shown in Fig. 4. This shaft is mounted on the upper arm 20 and with its outer end in a bearing on the outer end of an arm 31, as seen in Fig. 4. It is driven by a gear 32 splined and slidable on the shaft 30 which is driven by a gear 33 on a motor shaft 34 which is driven by an electric motor 35 carried by an arm 36 extending to the right from the main arm 20, as appears in Fig. 2. The gear 32 is moved into and out of mesh with the gear 33 by a hand-lever 37 pivoted at 38 on the frame arm 31, as seen in Fig. 4. By this means the spindle may be caused to rotate or not to rotate as desired.

The vertical reciprocation of the spindle is effected by the following means: There is a housing 40 at the upper end of the machine which extends up from the housing plate 27 heretofore mentioned. A horizontal shaft 41 is mounted therein, one end of said shaft having bearings in the end of the housing 40 and the other in a rib 42 extending up from the bottom of the housing, as seen in Figs. 1 and 3. There is splined or slidably mounted on the shaft 41 a hub 43 carrying a large spur gear 44 and a small spur gear 45. These gears are shifted by a hand lever 46 pivoted at 47 in the housing 40.

40 and the inner end of the lever is connected with the gear hub 43. This enables the shaft 41 to be driven by the gear 45 when it is in mesh with a gear 48 on a parallel shaft 49 on said housing 40, as shown in Fig. 3, or by the gear 44 when it is moved into mesh with a small gear 50 on the shaft 49. By this means a change of speed is obtained, the large gear 44 driving the shaft 41 at a low speed and the smaller gear 45 driving it at a higher speed. The shaft 49 is driven by a bevel gear 51 on the shaft 49 and a bevel gear 52 on a shaft 53 and mounted in the housing 40 at a right angle to the shaft 49 as seen in Fig. 3. The shaft 53 is driven by a sprocket wheel 54, sprocket chain 55 and sprocket wheel 56, the latter being mounted on the motor shaft 30, as seen in Figs. 2 and 3.

20 The foregoing means drives the shaft 41 constantly and when desired it drives a shaft 60 mounted in the housing 40 in alignment with the shaft 41, as seen in Fig. 1. To this end, the two shafts are clutched by a clutch member 61 on the driven shaft 60 being moved into clutching engagement with a clutch member 62 on the shaft 41, by a clutch lever 63, which is operated by a connecting rod 64 mounted in a bell crank 65 fulcrumed at 66 on an arm 67 extending up from the housing plate 27 heretofore described. The other arm of the bell crank lever 65 is pivoted at 68 to the upper end of the pedal-actuated rod 16, heretofore described. Hence, when the pedal 10 is depressed, the two shafts 41 and 60 will be clutched together and when the pedal lever 11 is released, the spring 14 will, through the intervening mechanism, release the clutch members 61 and 62 so that the shaft 60 will stop.

40 The shaft 61 vertically reciprocates the spindle 25, as shown in Fig. 1. Said shaft has secured on its outer end an eccentric 70 and said eccentric has mounted thereon an eccentric strap 71 which is secured to the eccentric by a screw 72 which extends through a slot 73 in the eccentric strap that is concentric with the axis of the eccentric 70, the screw 72 screwing into the eccentric. Thus the stroke of the eccentric strap construction is readily predetermined by releasing the screw 72 and angularly adjusting the eccentric strap 71 on the eccentric 70 to the desired position, and then tightening the screw 72. The slot 73 is substantially semi-circular so that the eccentric strap can be changed from the position shown in Figs. 1 and 2, which gives the extreme throw of the eccentric strap, to the position shown in Fig. 5, which gives the minimum throw of the eccentric strap.

60 The cam 71 has mounted on it an upper circular end of a member 74 which is pivoted at 75 to a ball race cap 76 in which the upper end of the spindle 25 is rotatably

mounted, so that as the ball race cap is elevated and lowered it will reciprocate the spindle, whether the spindle is rotated or not.

The operation of the machine will now be explained. The electric motor 35 may operate continuously and drive the shafts 34 and 41 constantly. If it be desired for the spindle 25 to rotate, the lever 37 shown in Fig. 4, is operated to bring the gears 32 and 33 in mesh, as they are shown. If it is desired that the spindle 25 shall not rotate, the lever 37 is operated to disengage the gear 32 from gear 33. Then the shaft 30 will not operate and the spindle will not rotate.

When it is desired to reciprocate the spindle vertically, the pedal lever 11 is operated by foot which clutches shaft 41 with shaft 50, but if it be desired not to operate the spindle, the pedal lever is not operated. Therefore, with this machine the spindle can be vertically reciprocated while being rotated or while it is not rotated and the spindle can be rotated while it is vertically reciprocated or not reciprocated. The eccentric strap 71 is adjusted in any position on the eccentric 70 to obtain the desired throw or vertical movement of the spindle 25. The vertical adjustment of the arm 21 carrying the work also, in addition to the means for controlling the vertical throw of the spindle, gives to the machine a wide range of operation.

If one desires to drill, a suitable drilling tool is secured to the lower end of the spindle 25. The gear 32 is put in mesh with the gear 33 so that the spindle, as shown in Fig. 4, will rotate. The handle 46, shown in Fig. 3, is operated to move the large gear 44 on the shaft 41 into mesh with the gear 48 so as to reduce to the minimum the speed of rotation of the shaft 41. Then the pedal is operated to clutch the shaft 60 with the shaft 41 which will cause a very slow vertical reciprocation of the spindle and at the same time it will be rotating and thus drill. By adjusting the eccentric strap 71 on the eccentric 70 the extent of the drilling operation can be governed.

While spinning the same procedure is followed excepting that a spinning tool is secured to the lower end of the spindle 25. While tapping the same procedure is followed excepting a tapping chuck is used.

If one desires to rivet, the gear 32 is thrown out of mesh with the gear 33, so that the spindle does not rotate. The handle 46 is operated to bring gear 45 into mesh with gear 48, as shown in Fig. 4, to obtain high speed of the shaft 41. Then the pedal lever 11 is operated to clutch shaft 60 with shaft 41. This will cause a rapid vertical reciprocation of the spindle 25 to the lower end of which a riveting tool is secured. This will give straight rapid blows for

upsetting the head of a rivet. While punching the same procedure as in riveting is employed, excepting the necessary change of tool, and the same is true while hammering.

While the machine shown in the drawings illustrates this invention, the invention is not limited to the details thereof as they may be varied without departing from the spirit 10 of the invention. *

The invention claimed is:

1. A combined metal working tool of the kind described, including a frame, a plurality of constantly driven shafts, a tool 15 carrying spindle reciprocable in said frame, means for reciprocating said spindle, means for clutching and unclutching the reciprocating means with one of said constantly driven shafts, means for rotating said 20 spindle, and means for operatively connecting said rotating means with the other one of said constantly driven shafts or disconnecting the same, substantially as set forth.
- 25 2. A combined metal working tool of the kind described, including a frame, a vertically-disposed spindle mounted therein so as to reciprocate, a spiral gear splined thereon so as to rotate the spindle and permit 30 its reciprocation, a spiral wheel meshing

with said spiral gear, a shaft on which said spiral gear is mounted, a constantly driven shaft, means for gearing said two shafts so that they may be operatively connected and disconnected, a shaft 35 operated means for vertically reciprocating the spindle, a constantly driven shaft in alignment with said last-mentioned shaft, a clutch for operatively connecting and disconnecting said shafts, and means for changing the speed of said last-mentioned constantly operating shaft.

3. A combined metal working tool of the kind described, including a frame, a vertically reciprocable spindle, a shaft for driving the spindle that is substantially at right angles therewith, an eccentric secured on said shaft, an eccentric strap surrounding the eccentric and angularly adjustable thereon, means for securing the eccentric strap to 50 the eccentric when adjusted, and a housing surrounding and moved by the eccentric strap and which is pivotally connected with the spindle, whereby the desired mode of operation and extent of actuation of the 55 spindle are obtained.

In witness whereof, I have hereunto affixed my signature.

FRANK RIESS.
